ABSTRACT OF THE DISCLOSURE

A chuck actuating device having a body with a cylindrical cavity and a double acting piston in the cavity. A main compressed air passage supplies air to the body through a rotary fluid connector and a four-way valve in the body controls the supply of compressed air to the opposite sides of the pistons. The valve is shiftable by fluid pressure supplied thereto via control passages also extending into the body through said rotary fluid connector. A resilient sealing ring check valve is interposed in the main air passage upstream of said four-way valve.

This invention relates to a rotary, compressed-air-actuated double-acting chuck cylinder for machine tools, and more specifically to a chuck cylinder of this type which has a four-way valve for reversing the direction of movement of the chuck piston, and with safety means for preventing a drop in pressure in the cylinder when the supply of compressed air is interrupted.

Rotary chuck cylinders for compressed air actuation have a pin rotating therewith, on which is mounted a stationary transfer housing for the connection of the pressure lines. The four-way valve for the reversal is generally arranged separately from the cylinder and is connected through two lines with the transfer housing.

If the air pressure fails and no special precautions are provided, the pressure in the cylinder would drop, and would do so instantaneously when a break occurs in the line. If the piston of the cylinder serves to actuate a chuck, a drop in pressure may lead to the release of a workpiece which would be spun off during rotation.

It is known to prevent the escape of compressed air from the chuck cylinder by check valves, which close on cessation of the pressure supply. Obviously it makes no sense to arrange such check valves in the stationary feeding line to or in the transfer housing, since then also the transfer from this housing to the rotary pin of the cylinder would be located in that part of the system which is to be blocked by the check valve. This transfer is however not always wholly fluid-tight and the leak may in the course of time become greater due to wear without causing difficulties during normal operation. However, on the cessation of the compressed air supply the air would in these circumstances escape at a more or less fast rate, and a shut-off would hardly help. It is for this reason that, it is customary to provide a check valve for each cylinder chamber directly on or in the cylinder or in the rotary pin. In order to make sure, when it is desired to release all pressure from the cylinder, that the compressed air can properly escape from said cylinder, it is necessary that the associated check valve be held open as long as necessary. To this end, in the heretofore known designs, each check valve is controlled by one auxiliary piston, or both check valves are controlled by an auxiliary piston common thereto. The auxiliary piston or pistons are for this purpose actuated by the actuating pressure for the respective other cylinder chamber.

These known arrangements of rotary chuck cylinders with two controlled check valves have proved satisfactory

2

insofar as even after many years of operation, in the case of the cessation of the compressed air supply in general even after many hours, a suitable operational pressure prevailed in the cylinder.

5 Rotary chuck cylinders with two check valves controlled by the actuation pressure have, however, two disadvantages, which under certain circumstances represent considerable drawbacks.

When a drop occurs in the air pressure or the air pressure fails completely, not only the cylinder chamber which is under pressure but also the cylinder chamber which is not under pressure will be off. When the two cylinder chambers, for example, through a damaged piston seal, communicate with each other, the pressure between the two piston chambers may equalize. Such a pressure equalization reduces the pressure difference generating the chucking force, so that the pistons can no longer exert a force while this cannot be observed from the outside. Under these circumstances, depending on the design of the chuck and the work situation, the workpiece may easily be pulled out or spun out, which by means of the check valve should have been specifically prevented.

In normal operation slight damage to the piston seal will not be harmful since a constant connection with the pressure air network exists. Only under the above described circumstances does it become particularly disadvantageous—however mostly by an accident which was to be avoided.

30 A further disadvantage of the heretofore known rotary chuck cylinders with two controlled check valves consists in the too small displacement speed of the chuck piston on reversal. This results from the fact, that during the movement of the piston in the cylinder—mostly only a small external resistance is to be overcome—the pressure difference between the two cylinder chambers is generally very small because the long and narrow lines throttle the inwardly and outwardly flowing air and because in view of the control by the auxiliary piston, of the check valve which control depends on the pressure difference, said check valve is only opened slightly. This again means an additional throttling and reduction of the pressure difference. As a result, in particular when working at low pressure, an important amount of time is lost.

45 It is, therefore, an object of the invention to provide a rotary double-acting pressure air-actuated chuck cylinder for machine tools of the hereinbefore described kind, which will afford an increased security against loss of chuck force during the loss of compressed air and in view of an increased speed of movement of the chuck piston during the reversal will permit a faster and thereby more economical manner of working.

50 These and other objects and advantages of the invention will appear more clearly from the following specification in connection with the accompanying drawings in which:

FIG. 1 is a longitudinal section through an embodiment of a chuck cylinder according to the invention.

FIG. 2 is a longitudinal section through a modified check valve for use in connection with the present invention.

60 According to the present invention there is provided a rotary double-acting chuck cylinder for a machine tool with a four-way valve for reversing the direction of movement of the chuck piston, which is characterized in that the four-way valve is arranged in the rotary part of the chuck cylinder between a single check valve and the cylinder chambers, while the path of the four-way valve for exhausting the compressed air from the cylinder chambers leads directly on the cylinder housing into the atmosphere.

65 The design according to the invention furthermore brings about that the cylinder chamber which is not under

pressure, will in case of failure of compressed air remain connected with the ambient air, so that even on the occurrence of an undesired connection between the two cylinder chambers, for example, due to a damaged seal, no pressure equalization between the two cylinder chambers can occur. While in this instance, the pressure in the cylinder chamber in which the chuck force is generated, may drop slowly, it does not build up simultaneously in the other chamber an increasing pressure, so that the pressure difference giving rise to the chuck force decreases only slightly.

Since the check valve in this arrangement is passed through by fluid only in one direction there is no need for it to be controlled. The connections between the four-way valve and the cylinder chambers are short and during the reversing operation increased speed of the chuck piston, also immediately after the start of the reversing operation and also at low operating pressure.

In view of the arrangement of the four-way valve directly ahead of the cylinder chambers, in accordance with the invention, the outlet of the four-way valve can directly be connected by the shortest path to the outside air. Consequently a trouble causing throttling of the outwardly flowing air cannot occur through passages of long bores and ducts.

According to a further feature of the invention the four-way valve is reversed by a pressure medium, which is controlled by a valve outside the cylinder housing and is conveyed through special control ducts into the rotating part through the stationary pressure medium transfer housing.

The four-way valve is according to a further feature of the invention designed as a control slide or valve spool having a sliding direction at right angles to the axis of rotation. This control slide may form a flat slide, which lies against a plane slide face under pressure and is displaceable between its end positions by a double-acting control piston.

According to a further feature of the invention both end positions of the control slide and of the control piston are symmetrical to the axis of rotation, and the common center of gravity of both parts passes at each adjustment position through the axis of rotation.

According to the invention it is further proposed, to provide a certain amount of play or lost motion between the control pistons and the control slide for the four-way valve, so that the control piston at each reversing action will have a lead and will be able to free or knock loose the control slide, if the latter should stick after long non-use. In this way, at the same time the distance of its center of gravity from the axis of rotation will be increased.

According to the invention it is furthermore proposed as pressure medium for the movement of the control piston to employ a fluid which will simultaneously serve for lubricating the pin journaled in the pressure medium transfer housing.

With regard to the construction of the embodiment of the check valve, it is proposed in accordance with the invention to form the check valve by an elastic ring which is so arranged that it flexes elastically under the influence of the inflowing compressed air, but springs back or returns to its original shape and position, when the flow ceases, and is pressed by the pressure prevailing in the space therebehind against a sealing surface.

The check valve may be made integral or of one piece with the pin, which by means of a flange is secured to the intermediate housing containing the four-way valve and contains a central supply or feed bore. Such an embodiment employs an O-ring, which is coaxial with the axis of rotation and is located in a groove having a wedge-shaped cross section. The bottom of said groove is through at least one radial bore in communication with the central supply bore in the pin of the cylinder housing. Another embodiment of the check valve may be in the form of a

grooved ring the open side of which faces away from the in-flow direction so that its elastic lip offers a resistance only to the return flow of the air but elastically flexes under the influence of the inflowing air.

5 The advantages of the double-acting chuck cylinder according to the invention are as follows:

Increased safety in case of network failure or line break, since not only is the compressed air prevented from escaping from the respective cylinder chamber under pressure, but also a substantially reduced pressure equalization between the two cylinder chambers will be prevented. The movement of the chuck piston is not slowed down because of long ducts or lines and additional throttling areas in the path of the exhaust air. For the reversal operations only small quantities of a pressure medium are necessary so that for this purpose thin pipes and small control valves will suffice. For the reversing operations, oil may be employed, which serves at the same time for lubricating the running and sealing surfaces of the pressure medium transfer housing. Whilst the cylinder rotates, accidental or undesired adjustments or displacements of the control slide are not possible. Finally only one check valve is required that does not have to be controlled and, therefore, can be designed extremely simple and safe in operation.

For this purpose, it is proposed in accordance with the invention that the check valve be made in one piece with the pin, which by means of a flange is secured to an intermediate housing containing the four-way valve. Simultaneously, the slide face may be formed on an insert secured within the cylinder housing which insert contains the connecting and transfer passages for the supply and exhaust of compressed air.

Referring now to the drawings in detail, the chuck cylinder, which is secured to the spindle (not illustrated) of a machine tool comprises a cylinder housing 1, which is closed by a cover 2, and has a chuck piston 3 slidable therein. The chuck piston 3 is provided with a piston rod 3a which transmits the movements and the force of the chuck piston 3 through the spindle to that part of the machine tool which is to be actuated, for example, the chuck jaws.

The movement of the chuck piston 3 is effected by compressed air, which is introduced into one of two cylinder chambers 4a and 4b. The supply of compressed air to the rotary cylinder housing 1 is effected through a pressure-medium transfer housing 7, which is supported on a pin 6 of the cylinder housing 1 and which delivers the compressed air supplied through a connection 8, into a central bore 11 in the pin 6. For this purpose, the stationary pressure medium delivery housing 7 is provided with an annular groove 7c, into which opens the connection 8 and which through a bore, remains in continuous communication with the central bore 11.

55 The pin 6 carries a flange 6a by which it is secured to an intermediate housing 5, which in its turn is disposed on the outer end of the cylinder housing 1. A four-way valve 13 is arranged in this intermediate housing 5 and comprises a control slide 13a and a control piston 13c.

60 The piston 13c is arranged in a through bore in the intermediate housing 5, which bore is closed at its ends by means of closure members 5a. The control slide 13a is biased by a spring 13b against a slide surface 14d in which the passages of the four-way valve 13 are disposed.

65 The connection between the control slide 13a and the control piston 13c is not positive, since the pin of the control slide 13a has a smaller diameter than the pin-receiving bore in the control piston 13c. This is clearly apparent from the longitudinal section of FIG. 1. In view 70 of this arrangement, the control piston 13c will prior to each adjustment travel over a short idle or dead path, as a result of which the control piston 13c will be able to knock loose or free the control slide 13a, if the latter should have become stuck after a long period of non-use.

In the illustrated embodiment, the slide face 14d is formed on an insert 14, which is with a flange 14c inserted into the cylinder housing 1 and which in addition to the communication passage 14b to the rear face of the cylinder chamber 4b additionally has a transfer passage 14a to the front cylinder chamber 4a. Since the transfer passage 14a leads into a central chamber 3c of the piston rod 3a, the piston rod 3a has a radially extending transfer bore 3b which leads to the front cylinder chamber 4a. That passage of the four-way valve 14 which serves for exhausting compressed air from the cylinder chambers 4a and 4b, leads in the illustrated embodiment to an exhaust bore 14e in the cylinder housing 1 which bore 14e communicates with the atmosphere.

A check valve 12 is arranged in the central bore 11 for the compressed air which bore 11 leads to the four-way valve 13. This check valve 12 comprises in the embodiment illustrated in FIG. 1, an elastic O-ring 12a, which lies in a groove 12b concentric with the axis of rotation X—X, said groove 12b being wedge-shaped in cross-section. The base of this groove 12b communicates through a plurality of radial bores 11c with the central bore 11 as is illustrated in the drawing. As soon as the pressure in the annular space outside the O-ring 12a exceeds the pressure in the central bore 11, the O-ring 12a is pressed into the wedge-shaped groove 12b, so that it will prevent back-flow of the compressed air in the central bore 11.

In the second embodiment of the chuck valve as illustrated in FIG. 2, in place of the O-ring 12a, a grooved ring 12d is employed the open side of which faces away from the in-flow direction. The elastic lip of the grooved ring 12d provides resistance only to the return flow of the air, whereas it is elastically deformed by the inflowing air.

The movement of the control slide 13a by means of the control piston 13c is effected by the pressure medium, which is supplied to the two opposing piston faces of the control piston 13c through control passages 10a, 10b respectively. These control passages 10a, 10b lead into the pin 6 in the region of the annular grooves 7a, 7b, which are arranged likewise in pressure-medium transfer housing 7 and are in communication with the control passage connections 9a, 9b respectively.

In the forward position of the chuck piston 3 as illustrated in the drawing, the rear cylinder chamber 4d communicates through the passage 14b the four-way valve 13a, the check valve 12 and the central bore 11 with the connection 8, so that the chuck piston 3 is held in the illustrated position. By means of the centrifugal force exerted on the control piston 13c and the control slide 13a these two parts of the four-way valve 13 are held in the illustrated position whilst the chuck cylinder rotates about its axis of rotation X—X.

If through a failure in the compressed air supply or through a rupture in the pressure air passage leading to the connection 8 the pressure in the central bore drops the check valve 12 would close immediately in as much as the O-ring 12a would press into the base of the groove 12b or the sealing lip of the grooved ring 12d would engage its sealing surface whereby the radial bores 12c would be sealed. The cylinder chamber under pressure is thus shut off, and the pressure can drop slowly only as a result of any leak due to a faulty seal. This would in practice take at least several hours. The other cylinder chamber remains in communication with the atmosphere through the control slide 13a so that the force acting upon the chuck piston 3 will be maintained. If this chuck piston 3 actuates for example a chuck the jaws of which must under no circumstances be allowed to release the work-piece as long as its rotates, the fact that the force acting upon piston 3 is maintained represents an active safeguard against accidents.

When the chuck piston 3 is to be reversed from its illustrated position at the forward end to the rear posi-

tion, whilst the chuck cylinder is stationary a pressure impulse is exerted through the control passage connection 9a and the control passage 10a upon the downwardly directed piston face of the control piston 13c as illustrated in the drawing so that this piston together with the control slide 13a is displaced beyond the intermediate position into the opposite end position. In this end position, the control slide 13a connects the communicating passage 14b with the outlet bore 14e, whereas the transfer passage 14a is connected with the central bore 11. The compressed air provided continuously through the connection 8, through the check valve to the four-way valve, then passes into the transfer passage 14a, the chamber 3c and the transfer bore 3b in the piston rod 3a of the chuck piston into the forward cylinder chamber 4a. In this way, the chuck piston 3 moves in the direction of the pin 6 of the chuck cylinder, whilst the compressed air in the rear cylinder chamber 4b is exhausted through the communication passage 14b through the exhaust bore 14e into the atmosphere.

Since the four-way valve 13 is located in the rotary part of the chuck cylinder, only one connection 8 is necessary. For reversing the four-way valve 13 when the chuck cylinder is stationary, short pressure impulses are sufficient. If a lubricating fluid is used as pressure medium for reversing the control piston 13a, lubricating fluid will simultaneously serve for lubricating the pin 6 rotating in the fixed pressure-medium transfer housing 7. Also, as will be apparent from the drawing, the chuck cylinder is of a particularly simple design, especially with regard to the arrangement of the slide surface 14d on the insert 14, in view of the arrangement of the four-way valve 13 in the intermediate housing and in view of the simple and yet operationally safe construction of the check valve 12.

It is, of course, to be understood that the present invention, is, by no means, limited to the particular showing in the drawing but also comprises any modifications within the scope of the appended claims.

What is claimed is:

1. A device for actuating the chuck of a machine tool and comprising: a body rotatable on an axis and having a cylinder cavity therein, a double acting main piston reciprocable in said cavity, a member connected to the piston to be reciprocated thereby and extending from the body for connection to a chuck part to be actuated, a spindle fixed to and projecting from said body on said axis, a sleeve rotatable on said spindle, a main passage extending through said sleeve and into and axially along said spindle for supplying compressed air to said main piston, a four-way valve in said body interposed between said main passage and the opposite sides of said main piston, exhaust passage means leading from said four-way valve to the atmosphere, said four-way valve being shiftable for selectively connecting a respective side of said main piston to said main passage while connecting the other side thereof to said exhaust passage means, control means operable for shifting said four-way valve, and means operable for preventing loss of air pressure to said main piston in the event of interruption of the supply of compressed air to said main passage, said means for preventing loss of air pressure to said main piston comprising a check valve in said main passage upstream of said four-way valve, said check valve comprising a valve seat and cooperating resilient sealing ring mounted on said spindle on said axis and elastically deformable by compressed air flowing in said main passage toward said four-way valve, said spindle near the end thereof nearest the four-way valve being provided with an annular groove communicating with said main passage at the bottom of the groove, said resilient sealing ring being mounted in said groove.
2. A device according to claim 1, in which said control means for shifting said four-way valve comprises opposed fluid operable areas connected to said valve, and control

passages leading through said sleeve and into and axially along said spindle to said fluid operable areas for supplying fluid thereto.

3. A device according to claim 1, in which said four-way valve comprises a slide member slidable at right angles to the axis on which said body is rotatable.

4. A device according to claim 3, in which said slide member is flat on at least one side, a valve plate in the body engaging one side of said member, passages leading from said valve plate to opposite sides of said main piston, a spring urging said slide member toward said plate, and a double acting control piston operatively connected to said slide plate, the opposite ends of such control piston constituting said opposed fluid operable areas.

5. A device according to claim 4, in which said slide member and control piston are symmetrically arranged with respect to said axis and have a common center of gravity which passes from one side of said axis to the other each time the slide member is shifted.

6. A device according to claim 4, in which the connection between said slide member and control piston provides for lost motion in the direction of movement of said slide member.

7. A device according to claim 2, in which the fluid pressure medium serving for controlling the shifting of said four-way valve is also a lubricant.

8. A device according to claim 1, in which the side walls of said groove converge toward the bottom of the groove and said resilient sealing ring is in the form of an O-ring engaging said side walls of the groove.

9. A device according to claim 1, in which said sealing ring has a resilient lip on one side engaging one wall of said groove and yieldable in response to pressure in the main passage upstream of said groove.

10. A device according to claim 1, in which said exhaust passage means comprises a single passage extending from said four-way valve through said body to the atmosphere.

5 11. A device according to claim 1, in which said groove is formed on said spindle at the body end thereof, a housing member mounted on said body and containing said four-way valve, and a flange on said spindle mounting the spindle on said housing member.

10 12. A device according to claim 4, in which said plate is in the form of an insert mounted in a wall of said body and includes a tubular portion projecting through said main piston, said passages leading from said four-way valve to the opposite sides of said main piston being formed in said plate and said tubular portion.
